US00D768181S

(12) **United States Design Patent** (10) **Patent No.:** **US D768,181 S**
Foss et al. (45) **Date of Patent:** **** Oct. 4, 2016**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Christopher Foss**, San Francisco, CA (US); **Chanaka Karunamuni**, Cupertino, CA (US); **Martin Pedrick**, San Francisco, CA (US); **Wan Si Wan**, Sunnyvale, CA (US); **Christopher Wilson**, San Francisco, CA (US)

(73) Assignee: **Apple Inc.**, Cupertino, CA (US)

(**) Term: **15 Years**

(21) Appl. No.: **29/541,140**

(22) Filed: **Sep. 30, 2015**

Related U.S. Application Data

(63) Continuation of application No. 29/457,361, filed on Jun. 10, 2013, now Pat. No. Des. 741,350.

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing our new design;

FIG. 2 is a front view of a display screen or portion thereof with graphical user interface showing our new design;

FIG. 3 is a front view of a display screen or portion thereof with graphical user interface showing our new design; and,

FIG. 4 is a front view of a display screen or portion thereof with graphical user interface showing our new design.

The broken lines in the figures show a display screen or portion thereof, and form no part of the claimed design.
